Primary Examiner — Deanna L Pratt*Assistant Examiner* — Harold Blackwell, II(74) *Attorney, Agent, or Firm* — Gudrun E. Huckett(57) **CLAIM**

The ornamental design for a casing, as shown and described.

DESCRIPTION

FIG. 1 is a perspective view of a casing showing a first embodiment of my new design;

FIG. 2 is a top plan view thereof;

FIG. 3 is a left side view thereof;

FIG. 4 is a right side view thereof;

FIG. 5 is a rear view thereof;

FIG. 6 is a front view thereof;

FIG. 7 is a bottom plan view thereof.

FIG. 8 is a perspective view of a casing showing a second embodiment of my new design;

FIG. 9 is a top plan view thereof;

FIG. 10 is a left side view thereof;

FIG. 11 is a right side view thereof;

FIG. 12 is a rear view thereof;

FIG. 13 is a front view thereof; and,

FIG. 14 is a bottom plan view thereof.
